(57) **CLAIM**

The ornamental design for a floating light signal device and portions thereof, as shown and described.

DESCRIPTION

FIG. 1 is a top perspective view of a floating light signal device;

FIG. 2 is a bottom perspective view thereof;

FIG. 3 is a front plan view thereof;

FIG. 4 is a rear plan view thereof;

FIG. 5 is a right-side plan view thereof, the left-side plan view being a mirror-image thereof;

FIG. 6 is a top plan view thereof; and,

FIG. 7 is a bottom plan view thereof.

The portions of the drawings shown in broken lines are intended for environmental purposes only and intended to form no part of the claimed design.
